AUTOMATIC COVER LIFT

Elmer Lehman, Ripon, Wis.

Application August 4, 1938, Serial No. 222,969

1 Claim. (Cl. 220—47)

This invention appertains to containers, and more particularly to a novel cover-raising and lowering device for wash machines, sterilizers, garbage, waste, and like containers or receptacles.

One of the primary objects of my invention is to provide a cover-operating mechanism embodying a foot treddle associated with the lower end of the container, and a rod connected with one side of the cover, with novel means between the rod and pedal so constructed and arranged that upon initial downward movement of the pedal, the rod will be raised vertically until the cover is lifted clear of the container, after which the rod and cover will be rotated, so that the cover will be swung off the container.

A further object of my invention is to provide a foot-operated device for the covers of receptacles embodying a combined reciprocating and rotatable rod connected with one side of the cover of the container, with means including a foot pedal for initially raising the rod and then rotating the rod.

A still further object of my invention is to provide a cover-operating mechanism of the above character, which will be durable and efficient in use, one that will be simple and easy to manufacture, and one which can be placed upon the market at a reasonable cost.

With these and other objects in view, the invention consists in the novel construction, arrangement, and formation of parts, as will be hereinafter more specifically described, claimed, and illustrated in the accompanying drawing, in which drawing:

Figure 1 is a rear elevational view of a container, showing my improved lid-opening device incorporated therewith.

Figure 2 is a top plan view of a container, with my invention associated therewith.

Figure 3 is an enlarged, fragmentary sectional view taken substantially on the line 3—3 of Figure 2, looking in the direction of the arrows, illustrating the novel mechanism between the foot pedal and the operating rod.

Figure 4 is an enlarged, fragmentary, detail sectional view taken substantially on the line 4—4 of Figure 3, looking in the direction of the arrows.

Referring to the drawing in detail, wherein similar reference characters designate corresponding parts throughout the several views, the letter C generally indicates a container including a body 5 and a cover 6. This container can be of any preferred character, size, or make, and has

associated therewith my novel cover-operating mechanism M.

My cover-operating mechanism M includes a vertically disposed operating rod 7, which extends longitudinally of the body 5 of the container, and this rod is mounted for rotatable, as well as reciprocatory movement. The upper end of the rod is securely fastened to one side of the cover 6 by means of a bracket 8, as is clearly shown in Figure 1 of the drawing. The lower end of the rod is connected to an actuating shaft 9. The shaft 9 can have its upper end provided with a socket for receiving a tongue or key 10 formed on the lower end of the rod. The upper end of the rod is guided in its movement in a suitable bearing 11 carried by the body 5 of the container adjacent its upper end.

The shaft 9 can be, and preferably is, mounted within a protecting housing or casing 12. This casing 12 can be secured to the container body 5 adjacent the lower end of said container. The upper end of the casing 12 has rigidly connected therewith a guide sleeve 13, through which extends the shaft 9. As shown, the guide sleeve 13 is formed with a longitudinal slot or guideway 14, and this slot communicates at its upper end with a semicircular slot 15, which is, likewise, formed in the sleeve. In direct axial alignment with the sleeve 13 is a socket or bearing 16 for receiving the lower end of the shaft 9. The shaft 9 extends into the sleeve and carries a radially extending pin 17, on which is rotatably mounted a roller 18 for engaging the walls of the grooves 14 and 15, as will be later set forth.

The shaft 9 has formed thereon or secured thereto a spiral thread or worm 19, for a purpose which will be later set forth. A collar 20 is, likewise, carried by the shaft, and is adapted to abut the top of the casing to limit the upward movement of the shaft and rod 7. If desired, the upper wall of the casing 12 can carry a ball-bearing raceway for the shaft 9.

Rockably mounted intermediate its ends on a pivot bolt is an actuating lever 21. This lever extends through a slot 23 in one wall of the casing 12, and the extreme outer end of the lever has formed thereon a foot pedal 24. The inner end of the lever has formed thereon a segment of a worm wheel 24', and the spiral teeth of the worm wheel segment engage the worm 19.

In operation of my improved device, downward pressure is exerted on the foot pedal 24 when it is desired to swing open the cover 6. This downward movement will raise the shaft 9 and the rod 7, due to the engagement of the worm wheel 55

segment 24 with the worm. As the roller 18 is confined in the vertical slot 14 in the sleeve, rotary movement of the shaft and rod is prevented. Hence, the cover will be lifted straight up and off the container body 5. However, when the stop collar 20 strikes the stationary obstruction, further upward movement of the shaft 9 and rod 7 is prevented, and if continued downward thrust is exerted on the lever 21, the inclined or spiral teeth of the worm wheel segment acting on the worm 19 will rotate the shaft 9 and the rod 7, and consequently swing the cover 6 off the container body 5, as shown in Figure 1.

A light touch of the fingers will swing the cover back over the container body, and thence downward into contact therewith.

From the foregoing description, it can be seen that I have provided an exceptionally simple and durable means for operating the closures of garbage and like cans.

Changes in details may be made without departing from the spirit or the scope of my invention, but what I claim as new is:

A receptacle comprising, a body, a cover removable from the body, and means for swinging the cover from said body including, a casing secured to the lower end of the body, a rod slidably and rotatably carried by the body extending into the casing, means rigidly securing the upper end of the rod to one side of the cover, a guide sleeve on the casing having a longitudinally extending slot and a semicircular slot connected at one end, a radially extending pin on the rod movable in said slots, a worm on the rod, a lever rockably mounted intermediate its ends in said casing, one end of the lever extending outward of the casing and having a foot pedal thereon, and a worm wheel segment on the inner end of said lever engaging the worm.

ELMER LEHMAN. 20
